Robert Wyatt

United States Patent Office.

ROBERT WYATT, OF BROOKLYN, NEW YORK.

Letters Patent No. 61,910, dated February 5, 1867.

IMPROVED SCRUBBING-BRUSH.

The Schedule referred to in these Letters Patent and making part of the same.

TO ALL WHOM IT MAY CONCERN:

Be it known that I, ROBERT WYATT, of Brooklyn, in the county of Kings, and State of New York, have invented certain new and useful improvements in Scrubbing-Brushes; and I do hereby declare that the following is a full, clear, and exact description of the same, reference being had to the accompanying drawings, making a portion of this specification, in which—

Figure 1 is a back view of a scrubbing-brush constructed according to my invention.

Figure 2 is a central longitudinal section of the same.

Similar letters of reference indicate corresponding parts in both figures.

This invention relates to that variety of scrubbing-brushes which are furnished with long handles, and designed chiefly for cleaning windows and the like. The invention consists in a brush hinged or pivoted upon the end of its staff or handle in such manner that it may be adjusted at any desired angle to the said handle, whereby the brush may be much more conveniently used for different purposes than if attached thereto permanently at any given angle. The invention further consists in a novel means of pivoting or attaching the brush to the handle, whereby the proper adjustment of the said brush is very much facilitated. The invention further consists in the combination with the brush and the staff thereof of a removable reservoir for containing water or suds, whereby the brush, while in use, is kept supplied therewith. The invention consists, furthermore, in certain novel means of attaching the reservoir to the brush for conveying the water or suds from the aforesaid reservoir to the said brush, and of preventing the escape of the water or other liquid from the reservoir through the opening through which it is poured into the same.

To enable others to understand the nature and construction of my invention, I will proceed to describe it with reference to the drawings.

The brush A, as represented in the drawings, is formed, with the exception of the wooden back a thereof, with a central portion, b, of sponge or other absorbent material, and an outer or circumferential portion, c, of bristles, but if desired, this brushing part of the brush may be made wholly of either of the aforesaid materials. Secured to the back a of this brush is a broad strip of sheet metal, the end portions of which are so bent and shaped as to constitute straps c', which are employed in holding the reservoir B in its place, as will be presently fully set forth, while the central part is doubled or shaped so as to constitute a flat plate, d, projecting out at right angles to the back of the brush, and which is fitted into a narrow slit, a', formed longitudinally in one end of the staff or handle C, and is pivoted therein by a transverse screw, e, which is furnished with a nut, f, between which and the side of the handle is a strong spring, g. By turning the nut f, the end of the handle is compressed so as to firmly clamp the plate d therein, and thus hold the brush A in a fixed position, the said brush being rendered capable of adjustment to any required angle, with reference to the handle C, by simply turning the screw e to loosen the hold of the handle upon the plate d. The reservoir B may consist of a rectangular sheet-metal box, which has attached to its under side two strong springs h which are doubled up, as shown more clearly in fig. 2, in such manner that when forced into and through the "straps" c' they will expand therein, and thus firmly and securely attach the reservoir to the brush. Extending from the bottom of the reservoir to the brushing portion of the brush A, are any desired number of small flexible tubes, i, which serve to convey the water, or other liquid contents of the reservoir, to the said brush, in order to keep the same in a properly wet condition. The opening or orifice through which the water or suds is poured into the reservoir is shown at k, and is formed in the uppermost side of the said reservoir, and has suspended from its inner edge or circumference a flexible bag or purse, m, made of any suitable material, and open at the bottom in such manner that water or suds poured in at the opening k is allowed to pass into the reservoir, while, when the apparatus is in use, the pressure of the water or other liquid causes the same to collapse, and thus close the opening k and prevent the "splashing" or escape of the water, etc., from the reservoir through the aforesaid opening k.

In using the apparatus, the brush A is adjusted at such an angle to the handle C as will best suit the convenience of the person using the same; and the reservoir D is filled with water or suds, as just hereinbefore described. The flow of the water, etc., through the small flexible tubes m keeps the brushing portion of the brush A properly saturated, and thus obviates the necessity of dipping the same into the water or suds, as

required in the scrubbing-brushes in common use, at the same time that any escape of the water through the opening *k* is effectually prevented by the collapsible bag or purse *m*, as hereinbefore explained, so that by these means the use of the brush is rendered much more expeditious and convenient than is the case with such ordinary brushes.

What I claim as new, and desire to secure by Letters Patent, is—

1. The attachment of the brush *A* to the handle or staff *C*, by means of the plate *d*, screw *c*, and spring *g*, substantially as herein set forth, whereby the brush may be adjusted at any desired angle to the said staff or handle.
2. The collapsible bag or purse *m*, arranged in relation with the opening *k* of the reservoir *B*, substantially as herein set forth for the purpose specified.
3. The combination of the reservoir *B*, brush *A*, springs *h*, and straps *c'*, substantially as herein set forth for the purpose specified.
